UNITED STATES PATENT OFFICE.

GEORGE WASHINGTON GOODWIN, OF SIMPSONVILLE, SOUTH CAROLINA.

SEED-PLANTER AND FERTILIZER-DISTRIBUTER.

SPECIFICATION forming part of Letters Patent No. 687,399, dated November 26, 1901.

Application filed April 6, 1901. Serial No. 54,745. (No model.)

To all whom it may concern:

Be it known that I, GEORGE WASHINGTON GOODWIN, a citizen of the United States, residing at Simpsonville, in the county of 5 Greenville and State of South Carolina, have invented a new and useful Seed-Planter and Fertilizer-Distributer, of which the following is a specification.

The invention relates to improvements in 10 seed-planters and fertilizer-distributers.

The object of the present invention is to improve the construction of combined seed-planters and fertilizer-distributers and to provide a simple, inexpensive, and durable one 15 which will be positive and regular in its operation and which will prevent clogging and insure a constant flow of the seed or fertilizer.

The invention consists in the construction and novel combination and arrangement of 20 parts hereinafter fully described, illustrated in the accompanying drawings, and pointed out in the claims hereto appended.

In the drawings, Figure 1 is a perspective view of a seed-planter and fertilizer-distributer constructed in accordance with this invention. Fig. 2 is a longitudinal sectional view of the same. Fig. 3 is a transverse sectional view; and Fig. 4 is a detail perspective view of a portion of the oscillatory shoe, illustrating the construction of the agitator. 25

Like numerals of reference designate corresponding parts in all the figures of the drawings.

1 designates a beam supported at its front 30 portion by a tappet-wheel 2, arranged to run on the ground and supported by a bearing-frame 3, consisting of a pair of approximately U-shaped loops secured at their inner sides to one of the faces of the beam and provided 35 at the lower terminals of their sides with registering perforations for the reception of an axle 4, upon which the ground or tappet wheel 2 is mounted. The wheel 2 is provided at one of its sides with an annular series of 40 tappets 5, arranged at regular intervals and adapted to successively engage and flex a resilient arm 6, secured to the lower face of an oscillatory shoe 7 and extending forward from the front end of the same, as clearly illustrated in Fig. 2 of the accompanying drawings. 45 The oscillatory shoe, which is pivotally mounted within a stirrup 8, tapers toward its

rear end, which extends between a pair of handle-bars 9, secured to the rear end of the beam and arranged in the usual manner, the 55 shoe being adapted to operate between the handle-bars and not requiring any change in the construction of the latter. The stirrup, which is approximately U-shaped, is composed of a horizontal bottom portion and vertical sides, which extend upward from the bottom portion and which have their upper ends bent outward at an inclination to conform to the configuration of the sides of a hopper 11 and secured to the same, whereby 60 the latter is supported in an elevated position above the beam, as clearly shown in Fig. 1. The bottom portion of the stirrup is disposed transversely and is secured to the upper face of the beam, and the hopper, which is of the 65 ordinary configuration, is also supported by an inclined brace 12, extending upward and rearward from the beam 1 to the front wall of the hopper. The oscillatory shoe, which is located beneath the bottom of the hopper, 70 is mounted on a transverse pivot 13, extending across a shoe; but any other suitable means may be employed for pivoting the sides of the shoe to the sides of the stirrup or bracket 8. 75

The planter and distributer is specially designed for distributing fertilizer and for planting oats, and when the tappet-wheel rotates forwardly the front end of the resilient rod or arm is flexed and when released springs 80 backward quickly and agitates the shoe sufficiently to discharge its contents into a tube or spout 14. This effect is materially increased by a bowed spring 15, arranged at the front of the shoe and extending upward 85 therefrom, as clearly shown in Fig. 1. The ends of the spring are secured to the front of the shoe at opposite sides thereof, and the top of the spring bears against the hopper, which is preferably provided with suitable projections 16; but the bowed spring may be engaged with the hopper in any other suitable manner. When the front end of the oscillatory shoe is raised by the flexing of the resilient arm or rod, the bowed spring is also flexed, 90 and it is adapted to assist in throwing the front end of the shoe downward quickly. The shoe is arranged at a slight inclination, and this continuous sudden vibratory motion 95

is adapted to discharge its contents into the spout or tube 14. The discharge spout or tube is mounted at the rear end of the beam and is preferably secured to the same, and its lower portion is located in the rear of a pair of standards 17, which is designed to be provided with a suitable shovel for opening a furrow, and covering-blades may be connected with the standards in the usual manner. 10 The flow of the material is regulated by an adjustable cut-off 18, mounted on the rear wall of the hopper and extending downward into the shoe, as clearly illustrated in Figs. 2 and 3 of the drawings. The cut-off is preferably slotted and is secured in its adjustment by a bolt 19 or other suitable fastening device. In order to prevent the oats or other material from clogging the discharge-opening at the bottom of the hopper, an agitator 20 is provided, and it consists of an approximately L-shaped piece extending rearward from the front of the shoe and projecting vertically into the bottom of the hopper. This L-shaped agitator may be mounted on the front of the shoe in any suitable manner and it may, as illustrated in Fig. 4, be provided with a double U-shaped bend 21, the inverted portion of the bend straddling the front wall of the shoe and the other portion being arranged at the front face of the shoe and secured to the front wall by bolts or other suitable fastening devices.

It will be seen that the combined seed-planter and fertilizer-distributer is exceedingly simple and inexpensive in construction, that it possesses great strength and durability, and that it is especially adapted for planting oats, as it is capable of preventing the same from clogging the discharge-opening of the bottom of the hopper. Furthermore, it will be apparent that the vibratory shoe is oscillated with sufficient force to discharge its contents into the spout or tube and that it is adapted to operate between the handle-bars, that the combined seeder and distributer may be readily thrown out of gear by simply pulling backward on the handle-bars to throw the front end of the resilient rod or arm beyond the path of the tappets, and that it may be readily arranged for operation by depressing the rear end of the shoe sufficiently to carry the resilient arm or stem into position to be engaged by the said tappets.

What I claim is—

55 1. The combination with a beam, and a tappet-wheel, of a stirrup mounted on the beam, a hopper supported by the stirrup, and an oscillatory shoe pivotally mounted between the sides of the stirrup, and provided with a resilient arm extending forward to the tappet-wheel and adapted to be engaged by the tappets thereof, said arm being adapted to be swung downward out of the path of the tappets by the backward movement of the tappet-wheel and being also adapted to remain

in such position until moved forward by the operator, substantially as described.

2. The combination with a beam, and a tappet-wheel, of a hopper, and an oscillatory shoe located in rear of the tappet-wheel and provided with an arm extending forward to the tappet-wheel and held in the path of the tappets by the forward movement of the wheel and being swung out of such position by the backward movement of the wheel, said arm being adapted to remain out of such engagement until moved forward by the operator, substantially as and for the purpose described.

3. The combination with a beam, and a tappet-wheel, of a stirrup mounted on the beam, a hopper supported by the stirrup, an oscillatory shoe mounted within the stirrup and provided with a resilient arm extending forward and downward to the tappet-wheel, and a spring mounted on the shoe and engaging the hopper and co-operating with the resilient arm to oscillate the shoe, substantially as described.

4. The combination with a beam, and a tappet-wheel, of a stirrup mounted on the beam, a hopper supported by the stirrup, an oscillatory shoe mounted within the stirrup and provided with an arm extending downward and arranged to be engaged by the tappet-wheel, and a bowed spring mounted upon the front end of the shoe and arranged to engage the hopper, substantially as described.

5. The combination with a beam, and a tappet-wheel, of a stirrup mounted on the beam, a hopper supported by the stirrup, an oscillatory shoe pivotally mounted within the stirrup and provided with an arm extending downward to the tappet-wheel and arranged to be engaged by the same, a brace arranged at the front of the hopper and secured to the same and the beam, projections arranged at opposite sides of the brace and extending from the hopper, and a bowed spring mounted on the hopper and engaging the projections, substantially as described.

6. The combination with a beam, and a tappet-wheel, of a hopper, a pivotally-mounted shoe located beneath the hopper and having an arm arranged to be engaged by the tappet-wheel, and an agitator mounted on the shoe and extending upward through the bottom of the hopper, substantially as described.

7. The combination with a hopper, and a vibratory shoe, of an agitator mounted on the shoe and carried by the same and extending into the bottom of the hopper, substantially as described.

In testimony that I claim the foregoing as my own I have hereto affixed my signature in the presence of two witnesses.

GEORGE WASHINGTON GOODWIN.
